UNITED STATES PATENT OFFICE.

JOHN G. SEKINGER, OF FORD CITY, PENNSYLVANIA, ASSIGNOR TO THE PITTSBURGH PLATE GLASS COMPANY, OF PITTSBURGH, PENNSYLVANIA, A CORPORATION OF PENNSYLVANIA.

MAGNETIC SEPARATOR.

1,259,788.

Specification of Letters Patent. Patented Mar. 19, 1918.

Application filed July 21, 1915. Serial No. 41,030.

To all whom it may concern:

Be it known that I, JOHN G. SEKINGER, a citizen of the United States, residing at Ford City, in the county of Armstrong and State of Pennsylvania, have invented certain new and useful Improvements in Magnetic Separators, of which the following is a specification.

The invention relates to magnetic separators, and the particular apparatus illustrated is designed for use in connection with crushed glass cullet from which it is desired to remove particles of iron, steel and the like. The invention has for its objects, the provision of a separator which shall be more effective in removing the iron and steel from the cullet or batch than those heretofore employed; the provision of a separator of cheap simple construction which can be applied to the end of any discharge chute; and the provision of a separator from which the iron collected can be easily and conveniently removed. One embodiment of the invention is illustrated in the accompanying drawings, 25 wherein—

Figure 1 is a side elevation of the apparatus constituting my improvement with a portion thereof in cross section, and Fig. 2 is a plan view of the lower end of the casing containing the electric winding with such winding and the cover plate removed.

Referring to the drawings, 1 is the lower portion of a hopper to which the crushed cullet is supplied; 2 is an inclined spout, or chute leading from the hopper; 3 is a casing preferably of cast iron containing the winding 4; 5 is a diagrammatic showing of a generator for supplying current to the winding; and 6 is a conveying bucket by means of which cullet fed through the spout and magnetic separator is carried to the furnace where it is used.

The opening 7 through the casing 3 is preferably rectangular in cross section as indicated in Fig. 2, and of less cross sectional area than the spout 2, the purpose being to retard the passage of the crushed cullet and to bring the material into close proximity with the sides of the casing, thus giving a better opportunity for the application of the magnetic cleaning force. The upper side of the trough 2 is open, as will be seen by reference to Fig. 1, so that the flow of material can be facilitated in case of

bridging or choking by means of an implement inserted from the upper side. This arrangement also permits of the use of a loose plate as a gate for controlling or stopping the flow of cullet, such plate being inserted upon the upper side of the casing 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390

The casing 3 is preferably a casting which is provided with the groove shown in Fig. 1 extending inwardly from its front side. This groove serves to divide the casing into two annular pole pieces 8 and 9, the space between being filled with the winding 4 with the turns thereof extending circumferentially of the opening 7. In order to protect the winding a cover plate 10, preferably of brass or similar non-magnetic material, is secured over the front end of the casing.

In operation, current is supplied to the winding 4 as the crushed cullet flows out through the opening 7, thus energizing the pole pieces 8 and 9. The iron and steel particles which happen to be in the cullet are brought relatively close to the pole piece 8 in their passage through the narrow elongated opening 7 and either adhere to the inner surface of the pole pieces or else are attracted to the lower end thereof as they emerge from the opening 7. The particles which adhere to the inner surface of the pole piece are shoved along by the flowing material and eventually come to rest on the lower surface of the cover plate 10. As the attraction is strongest at the lower ends of the pole pieces, the iron and steel particles finally collect in masses as indicated at 11 and 12. After the bucket 6 is removed and the current to the winding cut off, the material on the front face of the cover plate immediately drops off or can be scraped off without difficulty while another bucket is being brought into position. I have found that this apparatus very thoroughly cleans the cullet, requires little attention, and is not liable to get out of order.

What I claim is:

1. The combination with an inclined discharge spout, of a casing of magnetic material having an opening therethrough con-

stituting the outlet end of the spout and having its sides substantially parallel to the axis of the spout, and having a downwardly opening groove surrounding the said opening and dividing the inner and outer parts of the casing into pole pieces, and a winding in said groove with the turns thereof extending circumferentially of the said opening, the lower face of the casing being at substantially right angles to the axis of the winding and adapted to receive and support the magnetic material which passes through the casing.

2. The combination with an inclined discharge spout open on its upper side, of a 15 casing of magnetic material mounted on the end of the spout and having an opening therethrough in alinement with that of the spout but of less area in cross section, the said casing being provided with a downwardly opening groove surrounding the said opening and dividing the casing into two annular pole pieces, and a winding in the groove with its turns extending circumferentially of the said opening.

JOHN G. SEKINGER.
